C. C. FARMER

AUTOMATIC CAR COUPLER

Filed July 18, 1924

INVENTOR
CLYDE C. FARMER

BY Wm. M. Ladd.

ATTORNEY

UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC CAR COUPLER.

Application filed July 18, 1924. Serial No. 726,737.

This invention relates to car couplers, and more particularly to a combined car and air coupler of the tight lock type.

In a tight lock coupler, such as shown in the prior Westinghouse Patent No. 708,747, dated Sept. 9, 1902, there is provided a coupler head having a hook shaped portion adapted to engage a corresponding portion of counterpart coupler and having a pivoted locking lever or latch for tightly locking the coupler heads together.

With the above type of coupler, it has been found that after the coupler has been in service for some time and the latch portion has become worn, there is a possibility of the coupler heads uncoupling when not intended.

The principal object of my invention is to provide means for overcoming the above difficulty.

In the accompanying drawing; Fig. 1 is a sectional view of portions of coupled up tight lock couplers with my invention applied thereto; Fig. 2 a detail plan view 25 of the latch lock releasing mechanism; and Fig. 3 an end view of the mechanism shown in Fig. 2.

In Fig. 1, only so much of the coupler heads are shown as deemed necessary to illustrate the construction and operation of my invention, each coupler head 1 having a nose portion 2 adapted to engage a recess in the counterpart coupler head and the nose portion being provided with a surface 3 with which the cam face of a pivoted latch or lever 4 engages.

The latch 4 is provided with an operating arm 5 which is pivotally connected to a rod 6 operatively connected to a piston 7, contained in piston cylinder 8.

According to my invention, the arm 5 is provided with a plurality of notches, such as the notches 9, 10, and 11 and adapted to engage said notches is a pawl 12, which is pivotally mounted on a bracket member 13, secured to the coupler head 1. The bracket member carries a cylinder 14 containing a piston 15, which is connected through a piston rod 16 with the pawl 12.

For releasing the pawl 12 in the act of coupling, a member 17 is provided, which is rotatably mounted on the shaft 18 which carries the latch 4. Said member 17 is con-

nected through a link 19 with the end of the pawl 12.

In operation, when a coupler head is in the uncoupled position, the spring 20, acting on piston 7, tends to hold the latch lever 4 in its extreme counter clockwise position and the member 17 is held in the position shown in Fig. 1, by the spring 21, acting through piston 15, the piston rod 16, the pawl 12, and the link 19. When coupler heads are brought together for coupling up, the nose portion 2 of one coupler head will just engage the member 17 associated with the other coupler head and moving said member in a clockwise direction, will operate to trip the pawl 12 out of engagement with the notches in the arm 5. This permits a clockwise movement of the latch 4, so that the nose portion 2 can move into the coupled position, as shown in Fig. 1.

When the nose portion 2 assumes its coupled position, the latch 4 is swung in a counter clockwise direction by spring 20, so that the cam face thereof will engage the surface 3 of the counterpart coupler head and thus lock the coupler heads together.

The pawl 12 will then engage one of the notches of the arm 5 and will operate to lock the latch 4 and prevent any release movement thereof. A plurality of notches are provided in order to compensate for wear of the surface 3 and the engaging face of the latch 4. When new, the latch 4 may engage about as shown in the drawing and the pawl 12 will engage the notch 9 and as wear takes place, the latch 4 will move in further, so that the notches 10 and 11 will be successively engaged by the pawl 12, according to the amount of wear which has taken place.

In order to uncouple, a cock 22 in the motorman's cab is turned so as to simultaneously admit fluid under pressure through a pipe 23 to the piston cylinders 8 and 14. The piston 15 will be operated first; as the spring 21 is lighter than spring 20 and the pawl 12 will then be tripped from engagement with a notch in the arm 5. Fluid under pressure admitted to cylinder 8 then operates piston 7 so as to shift the latch 4 out of engagement with the engaging face 3 of the counterpart coupler head and thus permit the separation of the coupler heads.

A handle 24 is associated with the pawl 12, so that, if necessary, the pawl 12 may be tripped by operating the handle 24.

Having now described my invention, what I claim as new and desire to secure by Letters Patent, is:—

1. A car coupler comprising a rigid coupler head, a latch having a face for engaging a surface of a counterpart coupler head in the act of coupling for locking the coupler heads in engagement and means automatically operated upon the coupling of counterpart heads for positively locking said latch in its coupler locking position.

2. A car coupler comprising a rigid coupler head, a latch having a face for engaging a surface of a counterpart coupler head in the act of coupling for locking the coupler heads in engagement and a pawl for automatically engaging said latch in the coupled position to prevent movement of the latch from its coupled position.

3. A car coupler comprising a coupler head, a latch having a face for engaging a surface of a counterpart coupler head in the act of coupling for locking the coupler heads in engagement, a locking device automatically operated upon the coupling of counterpart heads for locking said latch in its coupled position, and fluid pressure operated means for operating said locking device to permit the uncoupling movement of said latch.

4. A car coupler comprising a coupler head, a latch for locking said head in engagement with a counterpart coupler head, a locking device for locking said latch in its coupled position, and means operated by the coming together of coupler heads in the act of coupling for releasing said locking device.

5. A car coupler comprising a coupler head, a latch for locking said head in engagement with a counterpart coupler head, a locking device engaging said latch for locking said latch in its coupler locking position, and means operated by the coming together of coupler heads in the act of coupling for tripping said locking device.

6. A car coupler comprising a coupler head, a latch for locking said head in engagement with a counterpart coupler head, a pawl engaging said latch for holding said latch in its coupler locking position, and means operated by a counterpart coupler in the act of coupling for releasing said pawl.

7. A car coupler comprising a coupler head having a nose portion and a pivoted latch for engaging a surface of a counterpart coupler in the coupled position, a pawl for holding said latch in its coupler locking position and a member operatively connected to said pawl and operated by the nose portion of a counterpart coupler head in the act of coupling for releasing said pawl.

8. A car coupler comprising a coupler head having a latch for locking said head in engagement with a counterpart coupler head, a piston operated by fluid under pressure for actuating said latch, a locking device for holding said latch in its coupler locking position, and a piston for operating said locking device.

9. A car coupler comprising a coupler head having a latch for locking said head in engagement with a counterpart coupler head, a piston operated by fluid under pressure for actuating said latch, a locking device for holding said latch in its coupler locking position, a piston operated by fluid under pressure for operating said locking device, and means for simultaneously supplying fluid under pressure to both pistons.

10. A car coupler comprising a coupler head having a nose portion for engaging a counterpart coupler head in the coupled position, and a pivoted latch for locking said head in engagement with a counterpart head and movable by the nose portion of a counterpart coupler head in the act of coupling, a locking device for locking said latch in its coupler locking position, and a member operatively connected to said locking device and movable by the nose portion of a counterpart coupler head to release said latch in advance of the movement of said latch by said nose portion.

11. A car coupler comprising a coupler head having a latch for locking said head in engagement with a counterpart head in the coupled position, said latch being moved away from its locking position by the counterpart coupler head in the act of coupling, a locking device for locking said latch against movement from its locking position, and a member operated by the counterpart coupler head in the act of coupling and in advance of the latch for releasing said locking device.

In testimony whereof I have hereunto set my hand.

CLYDE C. FARMER.
